OPERATING LEVER MECHANISM FOR
ROTARY HAND BRAKES

Keith Williams, Buffalo, N. Y.

Application October 3, 1947, Serial No. 777,641 Filed Oct. 3, 1947

3 Claims. (Cl. 74—142)

1

This invention relates to improvements in hand brakes of the swinging lever-operated type especially adapted for use on railway cars.

One object of the invention is to provide actuating means for the rotary chain-winding drum of a hand brake mechanism, comprising a swinging operating lever, a ratchet wheel rotatable with the drum, and a sliding pawl engageable with the ratchet wheel for operatively connecting the lever to the ratchet wheel to rotate the drum in chain-winding direction, wherein the lever in being swung in chain-winding direction pulls the pawl into engagement with the ratchet wheel, and swinging movement of the same in a reverse direction forces the pawl out of engagement.

A further object of the invention is to provide a hand brake mechanism comprising a chain-winding drum and means for transmitting rotary motion to the drum to wind the chain thereon, including a driving shaft, a ratchet wheel fixed to the shaft, a swinging link journaled on the shaft, an operating lever swingingly connected to said link, a pawl engageable with said ratchet wheel for locking the lever to the wheel to rotate the latter and the chain-winding drum, and an eccentric connection between the lever and pawl for effecting movement of the pawl into and out of engagement with the ratchet wheel as said lever is swung in reverse directions.

A still further object of the invention is to provide a mechanism as set forth in the preceding paragraph, wherein swinging movement of the lever is about a horizontal axis, thereby providing for automatic disengagement of the pawl from the ratchet wheel when the lever is dropped to pendent position and maintaining the pawl disengaged while the lever is in said pendent position.

Other objects of the invention will more clearly appear from the description and claims herein-after following.

In the accompanying drawing, forming a part of this specification, Figure 1 is a side elevational view of a hand brake mechanism, illustrating my improvements in connection therewith, said view showing the brake mounted on the end wall of a railway car. Figure 2 is a vertical sectional view, corresponding substantially to the line 2—2 of Figure 1. Figure 3 is an elevational view of the operating lever mechanism and cooperating ratchet wheel illustrated in Figure 1, showing in dotted lines the positions the parts assume at the initiation of the upstroke of the lever, and in full lines the positions assumed at the end of said upstroke. Figure 4 is an elevational view of the locking pawl of my improved mechanism, looking from the left in Figure 1.

My improved hand brake actuating means, as illustrated in the drawing, is shown as applied to a hand brake of the power-multiplying type,

2
enclosed in a housing 10 mounted on the vertical end wall 11 of a railway car. The hand brake illustrated is of the rotary drum type, comprising a drum 12 on which the brake chain (not shown) is wound. The drum is fixed to the usual horizontal shaft 13 suitably journaled in the housing walls. The shaft 13 carries a gear wheel 14 which is fixed thereto and is driven by a pinion 15 fixed to a second shaft 16 mounted in the housing below the shaft 13 and having its opposite ends journaled in the housing walls. The shaft 16 also carries the usual ratchet wheel 17 with which a sliding, spring-pressed locking dog 18 cooperates to hold the ratchet wheel 17 against rotation in chain-unwinding direction. The wheel 17 is arranged within the housing 10, being fixed to the shaft 16 adjacent to the pinion 15. A trip lever 19, of well-known form, is employed for actuating the locking dog to throw the same into and out of engagement with the ratchet wheel.

In carrying out my invention, I provide means for rotating the shaft 16 which is geared to the chain-winding drum 12, comprising broadly a lever A, a link B swingingly supporting the lever A on the shaft 16, a ratchet wheel C fixed to the shaft 16, and a sliding locking pawl D carried by the link B and operatively connected to the lever to be actuated thereby and lock the same to the ratchet wheel C.

The ratchet wheel C is mounted on a portion of the shaft 16 which is extended outwardly of the housing 10. As shown, the wheel C has a central hub member 20 projecting from opposite sides thereof and through which the shaft 16 extends. The wheel C is fixed to the shaft in any suitable manner, the hub member being preferably provided with an axial opening of square cross section, and the portion of the shaft 16 on which the wheel C is mounted being made of square cross section to fit said opening.

The link B comprises a pair of laterally spaced arms 21—21 joined by a transverse web 22 near the lower end thereof. At their upper ends, the arms 21—21 are slightly enlarged to provide rounded head portions 23—23. The arms 21 are disposed at opposite sides of the ratchet wheel C, the head portions 23—23 thereof being journaled on the projecting portions of the hub 20 of the ratchet wheel, each head being provided with a suitable bearing opening 24 for this purpose. The link B is held in position on the wheel C by a nut 32 threaded on the reduced end portion 33 of the shaft 16, with an interposed washer 34 bearing on the side of the link. The head portions 23—23 of the arms 21—21 are connected by a stirrup-like guide portion 25 at the right-hand side of said link, as seen in Figure 1. This stirrup-like guide portion comprises laterally extending short arms on the head portions 23—23

connected at their outer ends by a transverse cross piece.

The lever A is in the form of a bell crank member pivotally connected at its upper end to the link B and having a radially extending, forked, short arm 26 at its upper end. The pivoted upper end portion of the lever A is embraced between the lower ends of the arms 21-21 of the link B and is supported by a pivot pin 27 extending through suitable openings in the lever and arms of the link.

The locking pawl D is in the form of a short bar having a tooth 28 at its upper end engageable with the teeth of the ratchet wheel C. The pawl D is guided for sliding movement in the stirrup 25 of the link B and is slotted lengthwise between its ends, as indicated at 29, to provide clearance for the ratchet wheel, the slot 29 extending entirely through the pawl and having its upper end terminating at the tooth 28. The lower end portion of the pawl is reduced in width, as shown in Figure 4, said portion of reduced width being transversely enlarged to provide a head 30. This head of the pawl is pivotally connected to the forked arm 26 of the lever A, being engaged within the fork of said arm and connected thereto by a pin 31 extending through suitable openings in the head 30 of the pawl and the fork of the lever.

In the operation of my improved mechanism, in applying the brakes the operating lever A is oscillated, thereby effecting intermittent rotation of the ratchet wheel C and rotation of the drum 12 to wind the chain thereon. In swinging the lever A clockwise, as shown in full lines in Figure 3, there is also pivotal movement of the lever on the link B, thereby swinging the arm 26 clockwise, as shown in dotted lines in Figure 3, and pulling the tooth 28 of the pawl D into gripping engagement with the teeth of the wheel C, the pawl being directed in this movement by the guide stirrup 25 of the link B. Thus as the lever A is swung from the position shown in Figure 1 clockwise toward the full line position shown in Figure 3, rotation is imparted to the shaft 16 and the drum 12. During the return or counter-clockwise stroke of the lever, the lever first pivots on the link B, thus withdrawing the tooth 28 of the pawl D from engagement with the teeth of the ratchet wheel C to permit the return of the lever to the position shown in Figure 1 while the wheel C remains stationary, held in that position by locking engagement of the dog 18 with the ratchet wheel 17. Oscillating swinging movement of the lever A is continued until the brakes have been applied to the desired extent.

As will be evident, when the lever A is in the pendent position shown in Figure 1, it holds the tooth 28 of the pawl D disengaged from the teeth of the ratchet wheel C, thereby permitting free rotation of the latter and quick release of the brakes when the locking dog 18 is disengaged in the usual manner from the ratchet wheel 17 by the trip lever 19.

I claim:

1. In a hand brake mechanism, the combination with a rotary chain-winding member or the like, of means for transmitting rotary motion to said member to wind the chain thereon including a rotatable ratchet wheel, a swinging supporting member mounted for rotation about the axis of rotation of said ratchet wheel and extending radially therefrom, a pawl engageable

5 with said ratchet wheel on the side away from said supporting member and extending generally tangentially of said ratchet wheel and parallel to said supporting member, an operating bell crank lever swingingly connected to and constituting an extension of said supporting member and pivotally mounting said pawl for moving it into and out of engagement with said ratchet wheel and rotating the same by force applied to the side opposite the side where it is engaged by said pawl, and guide means extending from said swinging supporting member and holding said pawl for movement tangentially of said ratchet wheel.

15 2. In a hand brake mechanism, the combination with a rotary chain-winding member or the like, of means for transmitting rotary motion to said member to wind the chain thereon including a rotatable ratchet wheel, a swinging supporting member mounted for rotation about the axis of rotation of said ratchet wheel and extending radially therefrom, a pawl engageable with said ratchet wheel on the side away from said supporting member and extending generally tangentially of said ratchet wheel and parallel to said supporting member, an operating bell crank lever swingingly connected to and constituting an extension of said supporting member and pivotally mounting said pawl for moving it into and out of engagement with said ratchet wheel and rotating the same by force applied to the side opposite the side where it is engaged by said pawl, and guide means in the form of a stirrup extending from said swinging supporting member and slidably holding said pawl in operative relation to said ratchet wheel.

20 3. In a hand brake mechanism, the combination with a rotary chain-winding member or the like, of means for transmitting rotary motion to said member to wind the chain thereon including a rotatable ratchet wheel, a swinging supporting member mounted for rotation about the axis of rotation of said ratchet wheel and extending radially therefrom, a pawl engageable with said ratchet wheel on the side away from said supporting member and extending generally tangentially of said ratchet wheel and parallel to said supporting member, said pawl being slotted longitudinally and the teeth of said ratchet wheel extending into the slot, and an operating bell crank lever swingingly connected to and constituting an extension of said supporting member in operative engagement with said pawl for moving the same into and out of engagement with said ratchet wheel and rotating the same by force applied to the side opposite the side where it is engaged by said pawl.

KEITH WILLIAMS.
